(No Model.)

L. MÄCKE.
CUTTER.

No. 605,733.

Patented June 14, 1898.

UNITED STATES PATENT OFFICE.

LOUIS MÄCKE, OF CATSPRING, TEXAS.

CUTTER.

SPECIFICATION forming part of Letters Patent No. 605,733, dated June 14, 1898.

Application filed September 3, 1897. Serial No. 650,522. (No model.)

To all whom it may concern:

Be it known that I, LOUIS MÄCKE, of Cat-
spring, in the county of Austin and State of
Texas, have invented certain new and useful

5 Improvements in Cutters; and I do hereby
declare that the following is a full, clear, and
exact description of the invention, which
will enable others skilled in the art to which
it appertains to make and use the same, refer-
10 ence being had to the accompanying draw-
ings, and to the letters of reference marked
thereon, which form part of this specification.

This invention relates to certain new and
useful improvements in revolving cutters for
15 vegetables, fruits, and the like, and has for
its objects simplicity, durability, and cheap-
ness in construction, composed of a minimum
number of parts, and quick, accurate, and ef-
fective in operation.

20 A further object of the invention is to pro-
vide a cutter having a body composed of two
parts, whereby the device may be easily
cleaned, adjusted, or repaired, and to provide
a removable spindle, on which can be adjusted
25 knives, graters, or the like, as desired.

The invention consists of certain novel fea-
tures of construction and in combinations of
parts, more fully described hereinafter and
particularly pointed out in the claims.

30 In the drawings, Figure 1 is a perspective
view of my invention complete, the top being
opened and shown closed in dotted lines. Fig.
2 is a vertical central cross-section. Fig. 3 is
a side elevation, and Figs. 4 and 5 are eleva-
35 tions of a grater and knife disk, respectively.
Fig. 6 is an edge elevation of the cutting-
disk; and Fig. 7 is a similar view of a por-
tion of the disk, showing means for adjusting
the knives.

40 Referring by letters to the drawings, *a* is
the body of the cutter, and *b* is the movable
top, hinged at *c* and having fastenings *d*.

e and *e'* are uprights or supports provided
45 with clamps and set-screws or the like for
attaching the device to the edge of a table,
shelf, or other suitable place, and the flanges
of the other two supports or braces are fas-
tened to the surface of the table.

The upper ends of the two supports *e'* are
50 extended above the top *b* and form braces
against lateral strain or pressure from the
disks, and when closed a rod *f* is passed

through the said supports, which forms an
additional fastening against lateral strain
caused by the disk working against the side 55
of the box while cutting.

g is a spindle working in the journal-boxes
h, one half of which are carried by the body
and the other half by the top *b*, registering
and coinciding when the top is closed. 60

A suitable crank or handle *i* is provided to
revolve the knife or grater disks *j*, the knife-
disk being provided with a series of radial
blades *k*, arranged in a slanting position,
resting in slanting seats and adjustably se- 65
cured over the radial slots, leaving a space
through which the paring, sliced, or cut sub-
stance passes to the body of the cutter and
out through a suitable opening or discharge-
hopper *l*. 70

The spindle or shaft is provided with a
sleeve *m*, screw-threaded on its end and fits
over the spindle *h* and is adjustably secured
thereto by means of a set-screw. The sleeve
has lateral bearing enough on the shaft to 75
prevent any wobbling or oscillating motion.

In the movable top *b* is a receiving-hopper
b', into which the vegetables, &c., are poured,
sliding down and bearing against the rough-
ened surface of the grater-disk or against the 80
sharp projecting edges of the radial knives *k*,
which revolve and cut the meat or fruit and
allow it to pass to the discharging-hopper and
out of the cutter.

It will be observed that the cutting-knives 85
are removable and interchangeable as well as
adjustable, and it will be seen that the seats
of the knives are on an incline, the inclined
seat being formed in the metal of the face of
the disk, so that when the knife is inserted 90
in position the sharp edge has an outwardly-
set projection. The screw *n*, holding the
knives in position, is inserted in the inclined
seat portion *n'* of the knives, so that the head
will not interfere with the action of the 95
knife, the edge being on a plane beyond the
said head to set the knife-edge at an angle to
cut or slice a greater or less thickness, the
set-screws being adjusted to just the thick-
ness required and the shoulder in the disk re- 100
ceiving the thrust given to the knives in their
operation. These set-screws *n* are screw-
threaded in the disk and entered from the
back, so that their ends will come in contact

with the back of the knife and increase or decrease its cutting capacity, so that it will be seen that the inclined seat or bed in the disk, the inclined knives set at an angle, the two holding-screws, and the two adjusting or set screws are essential to the proper working of the cutting-knives, which in this device is a very valuable feature.

The disks are adjustable on the spindle by means of the sleeve *m*. Said sleeve is screw-threaded on and near its end, so that the knives and disks are adjustable and removable separately and independently of each other for joint operation.

The operation of the device is very simple and is as follows: The grater and knife disks being interchangeable either may be adjusted as desired. The top is then closed and fastened by means of the fastenings *d*, and the rod *f*, passing through the upright supports *e* and the disk, revolved by any suitable power or by hand by means of the crank and handle *i*. The vegetables are then placed in the receiving-hopper *b* and are cut or grated by the revolving disks *j*, the sliced or grated portion passing into the body *a* of the cutter and out through the discharging-hopper *l* in the bottom of the device.

Having thus fully described my invention and it being evident that various slight changes might be made in the forms, construction, and arrangement of the parts described without departing from the spirit and scope of the invention, hence I do not wish to limit myself to the exact construction herein set forth, but consider myself entitled to all such changes as fall within the spirit of my invention.

What I claim, and desire to secure by Letters Patent of the United States, is—

1. The combination in a cutter of the upper and lower hinged sections, each section carrying two halves of the journal-bearings, supports for said lower section, the support on one side forming clamps to clamp it to the edge of a table, and the supports on the opposite sides having flanges and adapted to be screwed to the surface of the table, one of said supports on each side extending above the upper section to receive a clamping-bolt to retain the said sections in position, and the other two supports extending above the lower section forming guides and stops for the upper section, against lateral pressure from the disk said disk being mounted upon a shaft in said bearings, all arranged for joint operation as set forth.

2. The combination in a cutter such as described having the upper and lower sections supports for the lower sections, the cutter-disks carried in the journals of said sections, the spindle of each disk having a removable sleeve, said sleeve being screw-threaded on the end for the interchange of cutter-disks, said disks having corresponding female screw-threads in their hubs, and adjustable on the spindle, and provided with adjustable cutter-knives, the knives resting in slanting grooves, the backs of said grooves forming supports for the knives whereby the strain is taken from the holding-screws, the upper sections being secured from lateral strain by the said support, substantially as set forth.

In testimony that I claim the foregoing as my own I affix my signature in presence of two witnesses.

LOUIS MÄCKE.

Witnesses:

LOUIS VON SCHMIDT,
HERMAN MEISTER.
